LINOLEUM CUTTER

Stanley F. Bobrowski, New Britain, and
Stanley L. Bobrowski, Bristol, Conn.

Application November 3, 1949, Serial No. 125,344

1 Claim. (Cl. 30—287)

1

This invention relates to cutters for thick sheet material such as linoleum and other floor coverings, and more particularly to a manually held and operated cutter which is adapted to cut strips of uniform width from the edge of a sheet of material.

One object of this invention is to provide a linoleum cutter of the above nature having guide means which is so arranged as to completely embrace the edge portion which is to be cut from the sheet, thus enhancing the accuracy of the cutter.

Another object is to provide a linoleum cutter of the above nature wherein the guide means comprises a gauge member adapted to embrace the edge of the sheet in advance of the cutting elements, so as to accurately locate the sheet for the beginning of the cutting operation.

Another object is to provide a manually-operated linoleum cutter of the above nature which is so constructed as to cut the sheet of material accurately without requiring special attention on the part of the operator for guidance of the cutter.

A further object is to provide a linoleum cutter of the above nature which will be simple in construction, inexpensive to manufacture, easy to use and manipulate, compact, ornamental in appearance, and very efficient and durable in use.

With these and other objects in view there has been illustrated on the accompanying drawing one form in which the invention may conveniently be embodied in practice.

In the drawings:

Fig. 1 is a plan view showing the improved linoleum cutter as it would appear when in use for cutting a strip from a sheet of linoleum, the latter being shown in broken lines.

Fig. 2 is a side view of the cutter, taken on the line 2—2 of Fig. 1.

Fig. 3 is a front view of the cutter, taken from the line 3—3 of Fig. 1.

Fig. 4 is a cross-sectional view of the same, taken on the line 4—4 of Fig. 1.

Fig. 5 is a longitudinal sectional view taken on the line 5—5 of Fig. 2, showing the interior construction of the cutter.

Fig. 6 is a side view of one of the double-toothed cutting elements.

Referring now to the drawings, in which like reference numerals denote corresponding parts throughout the several views, the numerals 10 and 11 indicate a pair of spaced-apart flat body plates having reduced rear end portions 12, 13, and a pair of out-turned coplanar flanges 14, 15 at the front ends of said plates.

2

In order to hold the body plates 10, 11 in spaced parallel relationship, provision is made of a pair of elongated spacers 16, 17, which are secured in parallel relationship between opposite edges of the reduced plate portions 12, 13 by means of a plurality of spot welds 18 in such a manner as to provide a channel 19, the axis of which extends at right angles to the flanges 14, 15.

In order to assist in holding the edge of a linoleum sheet L in a predetermined alignment between the body plates 10, 11, during the cutting operation, provision is made of a T-shaped gauge member 20 having an elongated flat stem 21 which is slidably received within the channel 19.

The gauge member 20 also comprises an integral narrow cross piece 22 which has its outer edge disposed in spaced parallel relationship to the plane of out-turned flanges 14, 15 between the plates 10 and 11, and extends outwardly of the edges of said plates. The upper end of the cross piece 22 (as viewed in Figs. 1 and 5) is provided with a pair of forwardly-extending flange pieces 23, 24 which diverge at their forward ends and are secured to said cross piece by any suitable means, such as a pair of rivets 25.

It will thus be seen that the edge of the sheet L of linoleum may be inserted between the flange pieces 23, 24, and against the outer edge of the cross piece 22 between the body plates 10, 11.

In order to hold the gauge member 20 against accidental changes of adjustment during the cutting operation, provision is made of a clamping screw 26 which is entered through a longitudinal slot 27 in the body plate 10 and is engaged in a tapped aperture in the stem 21.

In order to cut a slit S in the linoleum sheet L and thus sever a strip T therefrom, provision is made of a pair of thin flat cutting elements 28, 29 which are held tightly against the outer faces of the flanges 14, 15, respectively, by clamping blocks 30, 31, said blocks being held by pairs of screws 32, 33 engaged through said flanges.

As will be seen in Fig. 6, each of the cutting elements 28, 29 comprises a rectangular body portion 34 having a pair of apertures 35, and a pair of spaced V-shaped teeth 36, 37, the edges of which are sharpened. It will be understood that the apertures 35 are so spaced as to receive the screws 32, 33, which are entered through apertures in the flanges 14, 15 and through the apertures 35 so as to be engaged in tapped apertures in the clamping blocks 30, 31.

Provision is preferably made of spring washers 38 for preventing accidental loosening of the screws 32, 33.

It will be noted in Figs. 3 and 6 that the teeth 36, 37 disposed upon the cutting elements 28, 29, are laterally off-set in relation to their respective apertures 35, the cutting elements being so applied to the flanges 14, 15 that the teeth 36, 37 will be offset in the direction in which the linoleum L will normally move during operation of the cutter.

The cutting elements 28, 29 will preferably be so mounted that the adjacent points of their respective teeth 36, 37 will substantially engage each other, as illustrated in Fig. 3, although slight separation thereof will be unimportant.

As a means for determining the exact width of the strip T which is to be cut, the stem 21 of the gauge member 20 is provided with a graduated scale 39 which is preferably laid out in inches. The scale 39 is so located upon the stem 21 that the alignment of the graduations with the rear end 40 of the body plate 10 will accurately indicate the distance of the outer edge of the cross piece 22 from the cutting elements 28, 29.

Operation

In operation, the gauge member 20 will first be set so that the desired width of the strip T which is to be cut from the linoleum sheet L is indicated upon the scale 39. This will be accomplished by loosening the screw 26 and sliding the stem 21 longitudinally to the desired position, after which the screw 26 will be tightened. If the desired width of the strip T is to be one inch, for example, the graduation which indicates one inch will be set in alignment with the rear end 40, as shown in Fig. 1, whereupon the outer edge of the cross piece 22 of the gauge member 20 will be disposed exactly one inch inwardly from the cutting elements 28, 29, and parallel thereto.

A leading corner of the linoleum sheet L will now be inserted between the flange pieces 23, 24 and drawn downwardly while maintaining the edge of said sheet in engagement with the edge of the cross piece 22. Continued downward movement of the sheet L will cause the pairs of V-shaped teeth 36, 37 to cut into opposite surfaces of the sheet L so as to form a slit S which is exactly one inch from the edge of said sheet, thus forming a strip T having an accurate uniform width.

It will be noted that the opposite surfaces of the sheet L and the strip T will be confined by the body plates 10, 11 and also by the facing edge surfaces of the clamping blocks 30, 31 during operation of the cutter, thus maintaining the sheet L in a definite plane with respect to the points of the cutting teeth 36, 37.

In the event that the linoleum sheet L is large and cumbersome, it will be understood that there will be no necessity of moving said sheet during the cutting operation, inasmuch as the operator may easily grasp the cutter and move it manually with respect to said sheet, the direction of movement being upward, as viewed in Fig. 1.

Since the leading end portion of the cross piece 22 is well in advance of the cutting elements 28, 29, the operating force which is exerted upon the body plates 10, 11 by the use will tend to hold the gauge cross piece 22 firmly in engagement with the sheet and thus guide the cutting elements 28, 29 firmly along the line of the intended slit S.

It will be understood that if the pairs of projections 36, 37 are slightly separated so as to leave a thin web of uncut material intermediate the

thickness of the sheet L, said web may be easily broken by the operator by bending the strip T upwardly or downwardly after the cutting operation is completed. The operator may, in fact, prefer to operate the cutter in this manner in order to facilitate subsequent handling of the strip T, which may sometimes be very long and awkward to handle once it has become separated from the linoleum sheet L.

It has been found that the provision of two pairs of the V-shaped cutting teeth 36, 37 improves the operation of the cutter, and also provides very close control of the location and the form of the cut or slit S. This is due to the resiliency of the material being cut, which causes said material to yield to a certain degree when passing between a single pair of teeth so that the depth of the cut is not as great as would ordinarily be indicated by the depth of the teeth 36. The second pair of cutting teeth 37, being guided in accurate alignment with the slit S by the cross piece 22, will increase the depth of the cut made by the first pair of teeth 36 without material increase of the cutting resistance.

In the event that sharpening or replacement of the cutting elements 28, 29 should be required, said cutting elements may be readily removed merely by taking out the pairs of screws 32, 33 so as to release the clamping blocks 30, 31.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a cutter for sheet linoleum, a pair of spaced parallel body plates having an elongated T-shaped gauge member slidably disposed therebetween, the outer edge of said gauge member being disposed inwardly of the outer ends of said plates so as to form therewith a guide means for an edge portion of a sheet of linoleum to be cut, and a pair of cutting elements rigidly attached to outwardly flanges on the outer ends of said plates, respectively, said cutting elements extending inwardly at right angles to said plates for engagement with the opposite surfaces of said sheet while it is held by said guide means.
